(57) **CLAIM**

The ornamental design for a device for storing and supporting a smokable sleeve as shown and described.

DESCRIPTION

FIG. 1 is a top, perspective view of a device for storing and supporting a smokable sleeve.

FIG. 2 is a top, perspective view of the device for storing and supporting a smokable sleeve, with a drawer chamber in an open position relative to a sleeve body.

FIG. 3 is a front, plan view of the device for storing and supporting a smokable sleeve.

FIG. 4 is a back, plan view of the device for storing and supporting a smokable sleeve.

FIG. 5 is a left side, plan view of the device for storing and supporting a smokable sleeve.

FIG. 6 is a right side, plan view of the device for storing and supporting a smokable sleeve.

FIG. 7 is a top, plan view of the device for storing and supporting a smokable sleeve.

FIG. 8 is a bottom, plan view of the device for storing and supporting a smokable sleeve.

FIG. 9 is an unfolded, plan view of the drawer chamber of the device for storing and supporting a smokable sleeve; and,

FIG. 10 is an unfolded, plan view of the sleeve body of the device for storing and supporting a smokable sleeve.

The broken lines in the drawings depict portions of the device for storing and supporting a smokable sleeve that form no part of the claimed design.

1 Claim, 8 Drawing Sheets
